MEANS FOR NEUTRALIZING SOUND DISTORTION

Wesley Wilson, Chicago, Ill.

Application April 24, 1929, Serial No. 357,861
Renewed August 13, 1937

9 Claims. (Cl. 179—100.3)

My invention relates to translating devices (such as electrical sound reproducers, transformers, microphones, light control valves, etc.) and more particularly it contemplates the counteraction of distortion arising therein.

This invention is particularly adaptable to electrical circuits and energy transformers of sound recording and reproducing apparatus in which the permanent record is made on photographic film. These film records can be so made as to tend to counteract distortion arising within the recording and reproducing apparatus. This is not only an advantage in reducing distortion which can not be overcome by the methods of construction in vogue but also where a saving or simplification in the construction of the apparatus would be effected if it were not necessary to reproduce the record with perfect fidelity.

This invention is also adaptable to radio broadcasting and television, in which case the electrical impulses or waves could be distorted reversely at the broadcasting station to the distortion arising within the reproducing apparatus.

Another possible method of utilizing this invention is in secret communication such as teletypes and the transmission of pictures by radio. In this method it would be necessary to artificially cause distortion in the receiving apparatus to such an extent that the reverse distortion necessary in the sending apparatus (to counteract the distortion in the receiving apparatus) would be so great that the signal would be unintelligible if reproduced on apparatus not having the proper distortion.

Among the objects of my invention are to reduce the degree of distortion arising within translating devices by distorting the electrical waves (which operate or are operated by said devices) in the reverse direction to the distortion produced in the waves by the translating device; to tend to neutralize the distortion arising within sound or picture recording and reproducing apparatus by deliberately distorting the records (which are made and reproduced by this apparatus) in the reverse direction to the distortion arising within said apparatus.

A further object of my invention is to provide a method of correcting the effect of distorting characteristics in part of a sound controlling apparatus, comprising the introduction into the sound controlling apparatus of additional apparatus having distorting characteristics similar to the distorting characteristics of said part in such manner that the distortion caused by the intro-

duced apparatus counteracts the effect of the distortion produced by said part.

It will be understood that the following description relates more to this example of the practice of the invention and that the invention will be defined in the appended claims.

Further objects will appear from the description and claims.

In the drawings, in which several embodiments of my invention are shown—

Figure 1 is a diagrammatic view showing apparatus for making a sound record on photographic film and counteracting the effect of the distorting characteristics of the reproducing and recording apparatus;

Fig. 2 is a face view of a portion of the photographic film showing diagrammatically the direct sound record and the counteracting sound record;

Fig. 3 is a view similar to Fig. 2 but showing diagrammatically a different type of sound record;

Fig. 4 is a view showing diagrammatically the manner in which the two sound records of Fig. 2 may be combined in a single record at the side of the film;

Fig. 5 is a face view showing diagrammatically how the two sound records of Fig. 3 may be combined in a single record at the side of the film;

Fig. 6 is a diagrammatic view showing apparatus for reproducing the sound from photographic film similar to that shown in Figs. 2 and 3;

Fig. 7 is a diagrammatic view showing apparatus for counteracting at the broadcasting station the effect of distorting characteristics in the audiofrequency amplifier system of a radio receiving set;

Fig. 8 shows apparatus for counteracting the effect of distorting characteristics in amplifying and reproducing apparatus in which the counteraction or reverse distortion is effected electrically;

Fig. 9 shows apparatus for counteracting the effect of distortion arising within a loud speaker in which the reverse distortion is effected by energy dissipation; and

Fig. 10 is a chart showing curves plotted from the table at the end of the specification.

The basic idea underlying the various form of my invention shown is a method of correcting the effect of distortion arising within translating devices (such as electrical sound reproducers, transformers, microphones, light control valves, etc.) by utilizing additional apparatus having approximately the same distorting characteristics

as the device producing the objectionable distortion, in such a manner that the distortion caused by the introduced apparatus will have a counteracting effect with respect to the objectionable distortion. For example, if a film record is made of a violin solo by recording apparatus which produces distortion in the record in varying degrees and at certain definite frequencies it is obvious that this distortion will be reproduced in the reproducing apparatus. Now, if there is distortion also in the reproducing apparatus it is also obvious that this distortion will also show up in the reproduced violin solo. That is, there will be a variation in the equivalent value of the corresponding notes or frequencies in the original violin solo and the solo that is reproduced from the film record. If this same recording apparatus is used to make a record of the sound that is reproduced by passing the original record through the reproducing apparatus, it is obvious that in this second record, which we will call the secondary record, the equivalent value of the notes will vary from the corresponding notes in the original record at all points where there was distortion in the reproducing apparatus or in the recording apparatus as it was making the secondary record.

If in either the reproducing or recording apparatus the efficiency is very low when handling notes of one particular frequency it will result in the recording of this note on the secondary record at an equivalent value below that of the original record. Now, if the efficiency at this frequency was lowered in the recording apparatus it would mean that the equivalent value of the note on the original record would be lowered by this distortion and would again be lowered on the secondary record. If all of the distortion were in the reproducing apparatus at this frequency it would mean that on the original record this note would not have its equivalent value lowered but would be lowered on the secondary record. Therefore, in either case the equivalent difference between the two records would depend upon the distortion in the reproducing apparatus or in the recording apparatus when recording the secondary record. Or another way of saying it is that the equivalent differences between corresponding notes on the original and secondary records are similar to the equivalent differences between the notes of the original violin solo and the corresponding notes of the reproduced solo. Now, a way to neutralize this effect of distortion arising within the recording and reproducing apparatus is to distort the film record in the reverse direction to the distortion arising within said apparatus. That is, if the equivalent value of a particular note or frequency is lowered by distortion in either the recording or reproducing apparatus the film record should have this note recorded at a higher equivalent value in order to neutralize it. As the distortion recorded on the original and secondary records is in the same direction (but in different degrees) as the distortion arising within said apparatus, it follows that the desired film record (which will be called the neutralized record) should be distorted reversely to the distortion in the original and secondary record.

Now, as the equivalent value of notes on the secondary record have been lowered below the equivalent value of corresponding notes on the original record to the extent resulting from distortion caused by passing once through the reproducing and recording apparatus it follows that notes or frequencies which have been dis-

torted the most will have the greatest difference between their equivalent value on the primary and secondary records. If the notes or frequencies recorded on the secondary record are made to partially neutralize the corresponding notes on the primary record and the resultant effect recorded on a third film it will be found that this third film will be distorted in the proper direction to at least partially neutralize the effect of distortion arising within the said apparatus. By varying the degrees of neutralization between the original (primary) and secondary record when making the neutralizing record, it is possible to obtain the most advantageous degree of neutralizing distortion. Bearing in mind that the equivalent value of corresponding notes on the primary (original) and secondary records are identical when there is no distortion in the apparatus it becomes apparent that the notes that will be neutralized the most will be the ones that were weakened the least by distortion within the said apparatus. In actual practice this method is quite impractical and is of value only as a means of explaining the theory of the invention. Instead the electrical waves from the pick-up apparatus receiving the original sound waves are divided and made to flow through two parallel channels. One is provided with additional apparatus for producing distortion similar to the objectionable distortion and controls a light valve. The other channel also controls a light valve but has no additional apparatus for deliberately producing distortion. (This is similar to the system shown in Fig. 1 of the drawings.) The light fluctuations from these valves are recorded on the same film, either side by side (as shown in Figs. 2 and 3) so as to make two separate records (which would correspond to the original and secondary film records and which could be made to partially neutralize each other in the reproducing apparatus as in Fig. 6) or the two records could be superimposed (as shown in Figs. 4 and 5) if care were taken to insure that the recorded light from one valve neutralized the sound reproducing quality of the recorded light from the other valve, to such an extent as to produce the proper degree of reverse distortion.

The electrical waves from the two channels can be made to partially neutralize each other direct (as shown in Fig. 8) if a means is provided for maintaining the time lags in the channels identical. Such an arrangement would be adaptable to public address systems, radio telephony, the making of wax records for phonograph reproduction, etc.

Referring to the drawings in detail, and first to the apparatus shown in Figs. 1 to 3, inclusive, this comprises in general, apparatus for producing sound records on photographic films, which films, after having the sound record made thereon, may thereafter be used in the sound reproducing apparatus in Fig. 6. The apparatus shown in Fig. 1 comprises sound pickup which may be of any usual or suitable type, including input means 1 and amplifying means 2, a light control apparatus 3 controlled by the microphone for producing a sound-record on the film 4 corresponding to the received sound, and a corrective circuit for counteracting the effect of the distorting characteristics of the apparatus shown in Fig. 6 and also input 1 and amplifier 2. It is well known that reproducing apparatus, such as shown in Fig. 6, almost necessarily possesses distorting characteristics which will distort certain portions of the sound record more than it will distort 75

other portions; that is to say, certain frequencies may be reproduced well and with little loss of volume, while other frequencies may be reproduced poorly; that is, with considerable loss of volume. It is with a view to equalizing this distortion or loss of volume that the present apparatus is designed. In order to effect this equalizing or counteracting effect, certain apparatus is introduced into the recording apparatus of Fig. 1, including an amplifier 5 and speaker 6 (which should be identical with or similar to the amplifier 7 and speaker 8 of the apparatus of Fig. 6), receiving means 9 for sound transmitted by the speaker 6, which should have characteristics similar to input 1, amplifying means 10 (which should be similar to 2) for the receiver 9, and light control apparatus 11 for causing a sound record to be made on photographic film 4 which can be made to correct the effect of distortion due to the distorting characteristics of the reproducing apparatus of Fig. 6, and also input 1 and amplifier 2 of Fig. 1.

In order to take care of the time lag caused by the fact that the receiver 9 is necessarily placed an appreciable distance from the speaker 6, the recording point 12 of the light control apparatus 11 of the corrective circuit may be advanced a slight distance in the direction of film movement from the recording point 13 of the light control apparatus 3 of the direct circuit, the distance "A" having such a relation to the distance "B" that it will counteract the time lag due to the spacing between the receiver 9 and the speaker 6.

Bearing in mind that the amplifier 5 and speaker 6 of the corrective circuit have distorting characteristics substantially the same as the distorting characteristics of the amplifier 7 and speaker 8 of the reproducing apparatus of Fig. 6 and that the receiver 9 and amplifier 10 of Fig. 1 are similar to the input means 1 and amplifier 2 of Fig. 1, and also that the record made from light control 3 will correspond to the direct (primary) record, while the record made from light control 11 will correspond to the secondary record (which will be recorded in opposite phase). Recording in opposite phase may be accomplished by reversing the electrical connections, as shown clearly in Figs. 7, 8, and 9. Fig. 1 has a reversed connection between receiver 9 and amplifier 10 in that the upper conductor becomes the lower conductor on making the bend. It will be seen that there can be effected a partial neutralization of the direct record by the secondary record by properly adjusting light sources 25 and 26 of Fig. 6 which will produce the counteracting (reverse distorting) effect. Thus those parts of the record which would otherwise be reproduced with too great a volume will have this volume automatically cut down by the corrective circuit to a considerable extent, while those parts of the record which are relatively poorly reproduced in the apparatus of Fig. 6 will have their volume cut down comparatively little, by the corrective circuit of Fig. 1. By recording these two records on the same film no trouble should be encountered in permanently maintaining them in the proper phase relation. If recorded on separate recording medium this would be practically impossible to do. If the primary and the secondary records are made side-by-side, either as a variable density record as shown in Fig. 2, or as the variable width method as shown in Fig. 3, it will not be necessary to accurately control the relative intensities at which the two records are

recorded. All that is necessary is that the two records be 180° out of phase.

Fig. 2 shows one type of film record (known as the variable density type) which might be made by the apparatus shown in Fig. 1. The direct primary undistorted record 14 is alongside the secondary distorted record 15 with the corresponding portions in opposite phase (that is, one record passing the most light where the other record passes the least light). By using the entire width of the film for these records, the effect of film noises (caused by the granular structure of the photographic emulsion) is reduced.

This film record is adaptable for use on reproducing apparatus of Fig. 6. With such an arrangement the degree of reverse distortion is adjustable, it being necessary only to change the relative amount of light passing through the two records to vary the degree of partial neutralization. This is due to the fact that the sound reproduced in speaker 8 is dependent only upon the fluctuating component of the light striking the photoelectric cell and not upon the total quantity, the nonfluctuating component of light being

25

Fig. 3 shows a different type of record known as the variable width type in which the amount of light transmitted through the film is proportional to the width of the transparent portion 17 of the record. Otherwise it is the same as Fig. 2.

30

Fig. 4 shows a film in which the direct and secondary records 14 and 15 of Fig. 2 have been superimposed or combined into a narrow record 18 at the side of the film, leaving the rest of the film to be used for motion picture reproduction. With such an arrangement the degree of reverse distortion is fixed at the time the film is made and, therefore, must be accurately controlled in the making.

35

Fig. 5 shows a film in which the direct and secondary sound records of Fig. 3 have been combined into a single narrow sound record 19 at the side of the film leaving the rest of the film for the reproduction of motion pictures and is similar in characteristics to that of Fig. 4.

45

Fig. 6 shows the use of the sound record film 4 which is similar to the film shown in Fig. 2 or 3 produced by the apparatus of Fig. 1 in a sound reproducing apparatus having light apertures 20 and 21 for the direct and secondary sound record, feed apparatus 22 for the film, and a lens 23 for bringing the light which passes through the sound records into proper relation to a photoelectric cell controlling the amplifier 7 and speaker 8. Light from sources 25 and 26 is directed against apertures 20 and 21, respectively. Thereby having a separate light source for the direct and secondary records and thereby making it possible to manually vary the degree of reverse distortion continuously during the reproduction of a record so as to obtain the best results at all times.

55

Fig. 7 shows a method of reversely distorting a radio broadcasting signal so as to effectively neutralize the distortion in all receiving sets using a particular type of amplifier, amplifier 27 to be as nearly perfect as possible and to correspond to the direct circuit while amplifier 28 to be the same as that used in the said receiving sets, and to correspond to the secondary or corrective circuit. The output from amplifier 28 is made to partially neutralize that of amplifier 27 and thereby obtain this reverse distorting effect electrically. Amplifiers 27 and 28 may be of the push pull type so as to eliminate harmonics, etc.

70

75

Fig. 8 shows how it would be possible to accomplish this reverse distortion for neutralizing the distorting characteristics of a loud speaker without first permanently recording the sound. The fundamental difference between this circuit and the previous ones is in the way of avoiding the time lag encountered by the air gap "A" between speaker B and microphone C. This is accomplished by having two pick-up microphones D and E located at different distances from the source of sound. Microphone D picks up the sound for the circuit having the artificial distortion and which would correspond to the circuit used for the making of the secondary record of Fig. 1. Microphone E (which is located at a greater distance from the sound source than D) operates the circuit having no artificial distortion and which would correspond to that part of Fig. 1 which records the direct record. By properly adjusting the distance of microphone E from the sound source in relation to microphone D it will readily be seen that the time lag between speaker B and microphone C will be balanced out. When the sound which is to be picked up comes from many different points it is necessary that the mouth pieces of the microphones D and E be located side-by-side or even converge into one in order to obtain the proper time lag between the two microphones. This is accomplished diagrammatically in the figure in the form of a tube F which has the proper acoustical properties and extends from microphone E to a point adjacent to the mouth piece of microphone D.

Fig. 9 shows a still different way of carrying out the objects of this invention and consists of two parallel circuits, energized by the same source, which may be similar to each other with the exception that in one of the circuits a loud speaker is inserted (having characteristics similar to that of the speaker which is to do the final reproduction) in such a way as to dissipate the electrical energy impressed upon it in the form of sound energy. Now the frequencies at which the speaker operates most efficiently at will will also be the ones that have the greatest amount of energy dissipated. The result will be that the distortion produced in this circuit by this energy dissipation will be in the desirable direction. However, it will not be sufficient to produce the most advantageous results and, therefore, it will be necessary to partially neutralize by the relatively undistorted energy of the other circuit in order to increase this reverse distortion sufficiently.

Referring to Fig. 10, this is a diagram exhibiting the relative distortion correction that may be effected by the practice of my invention, as, for example, when using apparatus similar to that of Fig. 1. The vertical lines denoted by the letters "A to J", represent various frequencies handled by the apparatus and which correspond to the sound frequencies which are to be reproduced. The horizontal lines represent the relative energy levels at which the said various frequencies are reproduced, the scale of which is logarithmically shown to the left as the "relative energy levels shown in percent," while to the right are shown the corresponding values in TU (transmission units, defined by the equation $TU = 10 \log_{10} [P_1/P_2]$ when $[P_1/P_2]$ is the power ratio.) The linear relation shown by curve Q represents the relative reduction in volume of the various important frequencies of a recording and reproducing apparatus when employing no re-

verse distortion as practiced by this invention. The values for this curve are arbitrary and have conveniently been assumed to vary from 100% perfect reproduction to 10% perfect reproduction. It should be understood that any point on this curve may represent a large number of different frequencies that may happen to be reproduced with the same degree of efficiency.

The line P of Fig. 10 is assumed to represent the desired energy level at which all frequencies should be reproduced in order to give the proper volume of undistorted sound under a given condition.

The curve R of Fig. 10 represents the amount of distortion correction that may be effected by the practice of this invention when using apparatus similar in its distorting characteristics to the apparatus used to obtain curve Q.

At the end of the specification is a table showing how the arbitrary values for curve R have been obtained. In this table—

Column 1 denotes the various frequencies which are so distorted in the recording and reproducing apparatus as to produce curve Q.

Column 2 gives the arbitrary values in percent for the distortion arising within the recording apparatus.

Column 3 gives the relative percent of energy recorded on the original or primary film, and which are the same as the values of column 2.

Column 4 gives the arbitrary values in percent for the distortion arising within the reproducing apparatus.

Column 5 gives the resultant relative reproduction in percentage reproduced from the sound record of column 3 by the reproducing apparatus column 4.

The values in this column correspond to curve Q of Fig. 10.

Column 6 gives the relative percentage of the reproduction of column 5 that is recorded on the secondary record, when using recording apparatus having characteristics similar to that of column 2.

Column 7 gives the relative percentage of the recorded energy that is to be reproduced on apparatus similar to that of Fig. 6, when the energy recorded on the primary record of column 3 is partially neutralized by subtracting 80% of the secondary record of column 6.

Column 8 gives the relative percentage of reproduction obtainable for the various frequencies, when the partially neutralized record of column 7 is reproduced on apparatus similar to that of Fig. 6 and having characteristics similar to that of column 4. These values correspond to curve R of Fig. 10.

The comparison of curve Q and curve R of Fig. 10 shows quite clearly the result obtained by subtracting 80% of the secondary record from the direct record. This partial neutralization of one record with another has the effect of reducing the volume of the reproduced sound as well as tending to correct for distortion. Therefore, additional amplification will be required in the reproducing apparatus to overcome this reduction in volume. Curve R₂ shows the result obtained by increasing the amplification approximately four fold over that used in obtaining curve R.

If the reduction in volume, caused by distortion of the various important frequencies were such as could be represented by the letters A to F, and there were no frequencies reproduced as poorly as those represented by the letters G to

J, it would be necessary to subtract only about 70% of the secondary record from the direct record in order to obtain the most advantageous results. Column 9 and column 10 show the results obtained under this condition. Curve "S" of Fig. 10 which corresponds to the values given in column 10, shows clearly that the relative improvement is greater in this case than that of curve R and leads to the conclusion that the less the distortion within the apparatus, still greater will be the improvement effected by the present invention.

bining synchronously the products of two input apparatuses in parallel with each other, one of which input apparatuses is corrective and has distorting characteristics over said band of frequencies similar to the distorting characteristics of the reproducing apparatus, and applying said combined products to said reproducing apparatus. 5

5. A method of obtaining faithful reproduction of sound from sound-reproducing apparatus including an amplifier and a loud speaker, both having distorting characteristics over a substantial band of frequencies, which method comprises 10

15	Frequency	Relative % of energy passed by the direct recording circuit	Relative % of energy recorded on direct record	Relative % of energy passed by the reproducing circuit	Relative % of sound reproduced for secondary record	Relative % of energy recorded on secondary record	Direct record neutralized by 80% of secondary record, assuming that the energy output is the same for both primary and secondary circuits when operating at frequency "A"	Relative % of sound reproduced from neutralized direct record	15

I claim:

1. Sound recording means comprising a sound recording circuit for making a permanent record corresponding to the sound waves energizing said circuit, a sound reproducing circuit energized by the output of said recording circuit, and a second sound recording circuit having distorting characteristics similar to the distorting characteristics of said first recording circuit energized by sound reproduced by said reproducing circuit for making a second permanent record on the same recording medium as used for the recording from said first recording circuit.

45 2. A method of obtaining faithful reproduction of sound from sound-reproducing apparatus having distorting characteristics over a substantial band of frequencies which method comprises combining synchronously the products of two sound input apparatuses in parallel with each other, one of which input apparatuses is corrective and has distorting characteristics over said band of frequencies similar to the distorting characteristics of the reproducing apparatus, and applying said combined products to said sound-reproducing apparatus.

3. A method of obtaining faithful reproduction of sound from sound-reproducing apparatus including a loud speaker having distorting characteristics over a substantial band of frequencies, which method comprises combining synchronously the products of two sound input apparatuses in parallel with each other, one of which sound input apparatuses is corrective and includes a loud speakers having distorting characteristics over said band of frequencies similar to those of the loud speaker used in the reproducing apparatus and applying said combined products to said sound-reproducing apparatus.

70 4. A method of obtaining faithful reproduction of sense-affecting waves from reproducing apparatus having distorting characteristics over a substantial band of frequencies, which method comprises applying said waves to said apparatus com-

35 bining synchronously the products of two sound input apparatuses in parallel with each other, one of which input apparatuses is corrective and includes an amplifier and loud speaker having distorting characteristics over said band of frequencies similar to those of the amplifier and loud speaker, respectively, of the reproducing apparatus, and applying said combined products to said sound-reproducing apparatus.

40 6. Apparatus for obtaining faithful reproduction of sound from sound-reproducing apparatus having distorting characteristics over a substantial band of frequencies, which apparatus comprises two sound input apparatuses in parallel with each other, one of which input apparatuses is corrective and has distorting characteristics over said band of frequencies similar to the distorting characteristics of the reproducing apparatus, and means for combining synchronously the products of said two sound input apparatuses.

45 7. Apparatus for obtaining faithful reproduction of sound from sound-reproducing apparatus including a loud speaker having distorting characteristics over a substantial band of frequencies, which apparatus comprises two sound input apparatuses in parallel with each other, one of which sound input apparatuses is corrective and includes a loud speaker having distorting characteristics over said band of frequencies similar to those of the loud speaker used in the reproducing apparatus, and means for combining synchronously the products of said two sound input apparatuses.

55 8. Apparatus for obtaining faithful reproduction of sense-affecting waves from reproducing apparatus having distorting characteristics over a substantial band of frequencies, which apparatus comprises two input apparatuses in parallel with each other, one of which input apparatuses is corrective and has distorting characteristics over said band of frequencies similar to the distorting characteristics of the reproducing apparatus, and means for combining synchro-

65

70

75

nously the products of said two input apparatuses.

9. Apparatus for obtaining faithful reproduction of sound from sound-reproducing apparatus, including an amplifier and a loud speaker, both having distorting characteristics over a substantial band of frequencies, which apparatus comprises two sound input apparatuses in parallel with each other, one of which input apparatuses

is corrective and includes an amplifier and a loud speaker having distorting characteristics over said band of frequencies similar to those of the amplifier and loud speaker, respectively, of the reproducing apparatus, and means for combining 5 synchronously the products of said two sound input apparatuses.

WESLEY WILSON.
